WILLIAM H. HOOPER, OF LYNN, MASSACHUSETTS, ASSIGNOR, BY MESNE ASSIGNMENTS, TO THOMAS G. PLANT, OF BOSTON, MASSACHUSETTS.

INSOLE-REINFORCING MACHINE.

940,690.

Specification of Letters Patent. Patented Nov. 23, 1909.

Application filed December 23, 1907, Serial No. 407,639. Renewed April 14, 1909. Serial No. 489,848.

To all whom it may concern:

Be it known that I, WILLIAM H. HOOPER, residing at Lynn, county of Essex, and State of Massachusetts, and a citizen of the United States, have invented an Improvement in Insole-Reinforcing Machines, of which the following description, in connection with the accompanying drawings, is a specification, like characters on the drawings representing like parts.

The invention to be hereinafter described relates to boot and shoe making machines and more particularly to machines for applying a reinforcing material to insoles.

The object of the present invention is to provide a machine for this general purpose wherein a reinforcing material may be tucked into the channel formed by an upwardly and outwardly turned channel lip, the projecting edges of such fabric being trimmed at the upper portion of the lip, and the marginal portion of the sole outside the channel lip be consolidated, all of which and other objects will be best made clear from the following description in connection with the accompanying drawings, wherein one form or embodiment of the invention is presented for illustrative purposes.

In the drawings:—Figure 1 is a side elevation of a machine showing the invention embodied therein. Fig. 2 is a detached detail, partly in section showing the relation of the operating tools and their action upon the work. Fig. 3 is a face or front view of the parts shown in Fig. 2. Fig. 4 is a detail sectional view on line 4—4, Fig. 1.

In the embodiment of the present invention selected for disclosure herein, the column 1 carries a suitable head 2, in which is mounted for vertical movement the work supporting slide 3, Fig. 1. This work supporting slide 3 has a suitable bearing for the work supporting shaft 4, carrying at its outer end the work supporting and feeding wheel 5.

The work supporting slide is supported from beneath by a spring 6, which bears against said slide at its upper end and at its lower end is seated upon an adjusting screw 7, tapped into a lug 8 on the column. This screw is made tubular to receive the treadle rod 9, which extends upward through said spring and is connected at its upper end to

the work supporting slide 3. This treadle rod 9 and the well understood treadle connection (not shown) furnish means for depressing the work supporting and feeding wheel 5 for the introduction of the work, said spring thereafter lifting said work supporting and feeding wheel and its work to hold the latter firmly in position.

The work supporting shaft 4 at its inner end is operated by a connection 10 of any desired construction that will permit said shaft to be moved vertically by and with the work supporting and feeding wheel without losing its operative connection with the driving shaft 11, substantially alined therewith and turning in suitable bearings in the machine head. The driving shaft 11 is provided with a "Horton" or other suitable clutch device 12 which is operated by a radially extended arm 13 jointed to an eccentric rod 14, the eccentric 16 of which is fast upon the main driving 75 shaft 15 of the machine, said driving shaft being carried by suitable bearings 17 upon the machine head 2 and driven by the belt pulley 18 connected with any suitable source of power. Rotation of the main shaft 15 through the eccentric 16 and clutch device 12 will impart to the driving shaft 11, and, consequently, to the work supporting and feeding wheel 5, a step-by-step rotative movement.

Supported in a bearing 19 on the machine head is the obliquely disposed shaft 20 carrying at its upper end the consolidating or compression wheel 21, and at its lower end the beveled gear 22 which meshes with a correspondingly beveled gear 23 fast on the driving shaft 11. From the construction thus far described, it will be evident that rotative step-by-step movement imparted to the driving shaft 11 and work supporting and feeding wheel 5 will likewise be imparted to the consolidating and compression wheel 21, and a sole disposed between the work supporting and feeding wheel 5 and the consolidating and compressing wheel 21 will be given corresponding step-by-step movement.

Mounted upon a shaft or pin 24 carried in suitable bearings upon the machine head 2 is the tucking tool actuator comprising the arms 25 which carry between them at their lower portion the tucking tool 26, so dis-

posed that movement of the actuator about the pin 24 will give to the tucking tool 26 a reciprocating movement in a diagonal direction toward the surface of the work supporting and feeding wheel 5 for a purpose that will hereinafter appear.

Disposed between the arms 25 of the tuck-ing tool actuator is the knife actuator 27 mounted upon the pin 24, the lower end of said knife actuator being connected by a link 28 to a knife carrying slide 29, Fig. 2. The knife carrying slide 29 has a guide portion 30 which is received in an appropriately shaped seat of a fixed knife block carrier 31 and has extended therefrom a guiding stem 32 adapted for reciprocating movement in a bore 33 of the shaft 20, the construction and arrangement of the parts being such that as the shaft 20 rotates, the 20 knife carrying slide 29 and its connected parts 30 and 32, as just described, may reciprocate without partaking of such rotative movement.

The consolidating wheel 21, hereinbefore referred to, has its face portion recessed at 34 to receive the knife block carrier 31 which is itself supported by or connected to a fixed part of the frame of the machine head 2, Fig. 1. Seated within a suitable recess in the knife block carrier 31 is the knife block 35 having a cutting edge 36 to cooperate with a corresponding cutting edge of a knife 37 secured to the knife carrier 29, Figs. 1 and 2.

Secured to the main driving shaft 15 are the eccentrics 38, 39, each embraced by its eccentric strap 40 and 41 respectively. Seated within the end of the tucking tool actuator is a pin 42 having an eccentric outer portion 43, Fig. 4, embraced by the upper end 44 of the eccentric strap 40, the end of the actuator being preferably split as at 45 and provided with a clamping screw 46 for permitting rotative adjustment of the pin 42 therein and its subsequent retention in adjusted position. By the construction thus described, it will be clear that upon loosening the said screw 46, the pin 42 may be turned more or less, by means of its angular head 47, to change the position of its eccentric portion 43 in the end of the eccentric 40 to thereby change the path of movement of the actuator and, consequently, that of the tucking tool 26. Similarly, the lever 27 has its end provided with a split portion 48, a clamping screw 49 and a pin 50 with an eccentric head 51 embraced by the upper end of the eccentric strap 41, so that by loosening the screw 49, the pin 50 may be properly adjusted to change the path of movement of the knife 37.

It will be noted from the construction described, that the knife actuating lever or arm 27 is contained between the arms 28 of the tucking tool actuator and that the

knife 37 is, therefore, disposed directly above the tucking tool 26, so that in the operation of the machine the tucking tool 26 and the knife 37 act upon corresponding longitudinal portions of the work.

Referring to Fig. 2, the insole S is shown as properly positioned between the work supporting and feeding wheel 5 and the consolidating and compressing wheel 21, with the tucking tool 26 and the knife 37 respectively acting upon the reinforcing material. In this relation of the parts it will be noted that as the tucking tool 26 moves forward in an oblique direction to force the reinforcing material down into the bottom angular portion of the channel, and while it thus holds the reinforcing material from displacement, the knife 37 acts upon any projecting portion of the reinforcing material along the top of the channel lip, severing such projecting edge against the stationary edge of the knife block 35. The inclined or oblique movement of the tucking tool 26 is of peculiar importance in tucking the reinforcing fabric into a channel which is formed by turning a channel lip upward and outward or toward the sole edge, because the surface of the channel thus formed is of itself oblique to the surface of the sole. In thus acting upon the reinforcing material, the tucking tool 26 is in no sense a lip setting tool, it has no effect upon the already upturned lip other than to carry the reinforcing material into the channel on the inside of the channel lip and cause it to firmly adhere to the material of the insole, nor does it act as a clamp for the lip.

As hereinbefore stated, the work supporting and feeding wheel and the consolidating and compressing wheel are given a step-by-step rotative movement, and the insole 105 obviously partakes of this movement. Between each forward step of the insole, and while it is at rest, the tucking tool 26 and the knife 37 move forward into operative relation with the work and perform their functions, thus obviating any liability of disturbing the proper relation of the insole and the reinforcing material. It will be seen as noted also that the consolidating and compressing wheel 21 has compressing contact only with the outer marginal portion of the insole outside the channel lip, and that by such compressing action it consolidates this portion of the insole and carries the surface thereof substantially down to the surface of the reinforcing material when tucked into the bottom of the channel.

While details of structure have been an-
nounced as the preferred form of the present 125
invention, it is to be understood that the in-
vention itself is not circumscribed or re-
stricted to such details, other than as they
are defined by the claims, and changes in
the disposition and form of parts may be 130

made within the skill of the artisan without departing from the spirit of the present invention.

No claim is herein made for the broad idea 5 of providing in an insole reinforcing machine a tucking tool and trimming knife, the tucking tool acting in the direction diagonally to the surface of the insole, as such forms the subject matter of an application 10 of Charles P. Stanbon, Ser. No. 350,673, filed January 3, 1907, but

What is claimed is:—

1. In a machine of the character described, the combination of a work supporting and feeding wheel, a tucking tool, means to move it in a plane diagonal to the surface of the work to tuck the material into the channel formed by a lip turned upward and toward the sole edge, a compressing wheel acting 20 upon the sole edge outside the channel lip, a trimming knife, a stationary knife block associated therewith, and means for rotating the supporting and feeding wheel and the compression wheel.
2. In an insole reinforcing machine, the combination of a work supporting and feeding wheel, a tucking tool, means to move said tool in a plane diagonal to the surface of the insole to tuck reinforcing material 30 into the channel formed by a lip turned upward and outward, a trimming knife disposed above the tucking tool in the vertical plane thereof, and means for reciprocating said knife, said tucking tool and trimming 35 knife being simultaneously operative upon corresponding transverse portions of the reinforcing material.
3. In an insole reinforcing machine, the combination of a work supporting and feeding wheel, means for operating the said wheel step-by-step, a tucking tool, means to move said tool in a plane diagonal to the surface of the insole to tuck reinforcing material into the channel formed by a lip 45 turned upward and outward, a trimming knife disposed above the tucking tool in the vertical plane thereof, and means for reciprocating said knife, said tucking tool and trimming knife being operative upon corresponding transverse portions of the reinforcing material during the intervals between the step movements.
4. In an insole reinforcing machine, the combination of a work supporting and feeding wheel, means for operating said wheel and feeding the work step-by-step, a tucking tool, means to move said tool in a plane diagonal to the surface of the insole to tuck reinforcing material into the channel formed 55 by a lip turned upward and toward the sole edge, a trimming knife disposed above the tucking tool, a stationary knife block, and means for reciprocating the trimming knife, said tucking tool and trimming knife acting substantially simultaneously upon corre-

sponding transverse portions of the reinforcing material during the intervals between step movements of the work.

5. In an insole reinforcing machine, the combination of work feeding means and operating devices therefor, a tucking tool, means for moving it in a plane diagonal to the surface of the sole to tuck the material into the channel formed by a lip turned upward and toward the sole edge, a trimming knife and its carrier, means for sliding said carrier, and a stationary knife block co-acting with the sliding knife, said tucking tool and trimming knife acting conjointly to tuck and trim the reinforcing material at the same transverse portion.

6. In an insole reinforcing machine, the combination of a work feeding wheel and a consolidating wheel acting on the margin of the sole and devices for giving them step-by-step movement, a tucking tool, a tucking tool actuator for moving said tool in a direction diagonal to the surface of the sole to tuck the material into a channel formed by a lip turned upward and outward, a trimming knife arranged above the tucking tool in a vertical plane thereof, and means for operating the trimming knife, said tucking tool and trimming knife acting upon the reinforcing material during its intervals of rest.

7. In an insole reinforcing machine, the combination of a work supporting and feeding wheel, a consolidating wheel for acting along the marginal portion of the sole and having a recessed face, a stationary knife block supported in the recessed face of said wheel, a trimming knife, and means to reciprocate it for co-action with said stationary knife block to trim the edge of the reinforcing material along the upper portion of the channel lip.

8. In an insole reinforcing machine, the combination of a work support, a tucking tool, a tucking tool actuator comprising arms 25 by which the tucking tool is held, a knife carrier disposed between the arms of the tucking tool actuator and provided with a knife arranged above the tucking tool, and means for operating the actuator and knife carrier.

9. An insole reinforcing machine, comprising in combination, a work support, a tucking tool, a tucking tool actuator to move the tucking tool in a direction oblique to the surface of the insole to carry the reinforcing material into the channel formed by a lip turned upward and outward, a trimming knife carrier, a trimming knife mounted thereon above the tucking tool, said tucking tool actuator and trimming knife carrier being relatively constructed and arranged to cause the tucking tool and trimming knife to act upon the reinforcing material in the same transverse plane.

10. An insole reinforcing machine com-

prising in combination, a work support, a tucking tool, a tucking tool actuator to move the tucking tool in a direction oblique to the surface of the insole to carry the reinforcing material into the channel formed by a lip turned upward and outward, said actuator including two supporting arms between which the tucking tool is held, a knife carrier disposed between said supporting arms, 10 a knife mounted thereon above the tucking tool, and means to move said knife.

11. An insole reinforcing machine, comprising in combination a work support, a tucking tool, a tucking tool actuator comprising arms by which the tucking tool is

held, a sliding knife carrier disposed between the arms of the tucking tool actuator and provided with a knife arranged above the tucking tool, means for operating the actuator and knife carrier, and means for varying the path of movement of said tucking tool and knife carrier.

In testimony whereof, I have signed my name to this specification, in the presence of two subscribing witnesses.

WILLIAM H. HOOPER.
